(57) CLAIM

The ornamental design for a picnic table and bench covering set, as shown and described.

DESCRIPTION

FIG. 1 is a perspective view of a picnic table and bench covering set showing my new design, shown in condition of use;

FIG. 2 is a top plan view thereof, showing only the table covering;

FIG. 3 is a bottom plan view thereof;

FIG. 4 is a right-side elevation view thereof;

FIG. 5 is a left side elevation view thereof;

FIG. 6 is a front elevation view thereof;

FIG. 7 is a rear elevation view thereof;

FIG. 8 is a top plan view of a picnic table and bench covering set, showing only the bench covering;

FIG. 9 is a bottom plan view thereof;

FIG. 10 is a right-side elevation view thereof;

FIG. 11 is a left side elevation view thereof;

FIG. 12 is a front elevation view thereof; and,

FIG. 13 is a rear elevation view thereof.

The broken lines in the figures are to show environment and form no part of the claimed design.

The additional broken lines in the figures are for the purpose of illustrating portions of the picnic table and bench covering set, which form no part of the claimed design.

1 Claim, 8 Drawing Sheets
